UNITED STATES PATENT OFFICE.

JOHAN FERDINAND JULIUS CLEMENTSON, OF MÄLMO, SWEDEN.

REVERSING-GEAR FOR PROPELLER-SHAFTS.

1,320,316.

Specification of Letters Patent. Patented Oct. 28, 1919.

Application filed January 6, 1919. Serial No. 269,945.

To all whom it may concern:

Be it known that I, JOHAN FERDINAND JULIUS CLEMENTSON, a citizen of Sweden, and a resident of Malmö, Sweden, have invented a new and useful Improvement in Reversing-Gear for Propeller-Shafts, of which the following is a specification.

This invention relates to a novel improvement in reversing gear for propeller shafts 10 for outboard motors.

The object of the invention is to provide a simple and reliable construction of reversing gear for said purpose by using only one shaft and avoiding separate couplings 15 between the toothed wheels.

The invention is illustrated in the accompanying drawing:—Figure 1 is a vertical, sectional view of the whole arrangement: Fig. 2 is a side view of a part of the steering and reversing lever mechanism. Fig. 20 3 is a horizontal, sectional view, taken through the motor shaft and its sleeve at the level of the pivot pin of the steering lever. Fig. 4 is a horizontal, sectional 25 view, taken through the motor shaft and its sleeve farther down.

The motor 1 is provided with a vertical, hollow crank shaft 2, in which the upper end of a prolongation 4 of said shaft is 30 vertically slideable. In the crank shaft a vertical groove 3 is provided in which a key 5 on the prolongation 4 is fitted. The sleeve 8 surrounding the shaft carries a bracket in which the horizontal pivot pin 35 9 for a steering and reversing lever 6 is mounted said lever having a forked part embracing the bracket and the sleeve 8. The lever 6 is movable vertically in a known way after loosening the catch 7 and 40 it is pivotally connected with two arms 10 (Figs. 2 and 3) which at their lower ends are connected with a ring 12 or the like which is prevented from sliding vertically by means of a sleeve or the like 11. When 45 the lever 6 is moved vertically around the pivot pin 9, that is perpendicular to the shaft 4 this latter will be lifted or lowered.

The sleeve 8 is connected with the casing 13 by means of a pipe 23 surrounding the 50 shaft 4. The casing 13 carries the rudder 28 and bearings for the propeller shaft 16. Two bevel gear wheels 14, 15 are mounted on the shaft 4 and fixed thereto axially and 55 radially. One of these wheels is placed on each side of another bevel gear wheel 17

fastened to the propeller shaft 16. When the shaft 4 is raised or lowered the one or the other of the wheels 14 and 15 may be brought into engagement with the bevel gear wheel 17. By lifting the lever 6 from 60 E to F or G the shaft 4 will be raised either in such a way that both wheels 14, 15 are brought out of engagement with the wheel 17 or so that the wheel 15 is engaged with the same instead of the wheel 65 14, as shown in the drawing.

The motor is in a known way suspended over the stern of the boat by means of a stirrup 19 and a clamping screw 20. The boat is steered by means of the lever 6 by 70 moving the same horizontally, and the sleeve 8 is at the upper end provided with a flange 21 that is made to turn in a groove formed between a ring 22 or the like and a recess in the motor casing.

By the construction described loose gear wheels are done away with and all the advantages mentioned above are gained.

Having thus described the invention, I claim:—

1. Reversing gear for propeller shafts in connection with outboard motors comprising a prolongation of the crank shaft of the motor, said prolongation being made to slide axially and provided with two bevel 85 gear wheels fixed on the same axially and radially, one on each side of a bevel gear wheel fastened on the propeller shaft, a steering lever connected with the prolongation by means of arms in such a way that 90 one or the other of the fixed gear wheels on said prolongation will be brought into or out of engagement with the wheel on the propeller shaft.

2. In apparatus of the character described, a substantially vertical power shaft, a vertically movable drive shaft having a slideable keyed engagement with the power shaft, a propeller shaft arranged at substantially a right angle to the drive 100 shaft, a bevel gear carried by the propeller shaft, upper and lower bevel gears carried by the drive shaft and arranged upon opposite sides of the first named bevel gear, and means to shift the drive shaft longitudinally.

3. In apparatus of the character described, a suitably supported substantially vertical bearing, a power shaft journaled in the bearing, a vertically movable drive 110

shaft having a slideable keyed engagement with the power shaft, a horizontally turning sleeve pivoted upon the bearing, a vertical swinging lever pivotally connected 5 with the sleeve to turn it and connect it with the drive shaft to raise and lower it, a gear casing carried by the sleeve, a propeller shaft carried by the gear casing, a bevel gear secured to the propeller shaft, 10 and upper and lower bevel gears carried by

the drive shaft and arranged upon opposite sides of the first named bevel gear.

In testimony whereof, I have signed my name to this specification in the presence of two subscribing witnesses.

JOHAN FERDINAND JULIUS CLEMENTSON.
